Patented Dec. 1, 1959

186,808

COMBINED CARD HOLDER, ASH TRAY, AND RECEPTACLE FOR SMOKING ARTICLES

Clifford R. Barnes, Sandusky, Ohio

Application July 29, 1958, Serial No. 51,984

Term of patent 3½ years

(Cl. D85—2)

—1—

—2—

Figure 1 is a perspective view of a combined card holder, ash tray and receptacle for smoking articles, showing my new design; and

The back is substantially plain and unornamented.

I claim:

The ornamental design for a combined card holder, ash tray and receptacle for smoking articles, as shown and described.
